UNITED STATES PATENT OFFICE.

GEORGE J. LESSARD, OF SANTA MONICA, CALIFORNIA.

HASP.

Application filed June 23, 1928. Serial No. 287,788.

My present invention has reference to an improvement in a hinge hasp.

The primary object of the invention is the provision of an extensible hasp of a nature and construction whereby the same will properly engage with the staple therefor, regardless of the expansion and contraction of the door upon which the staple or the hasp is fixed.

10 A further object is the provision of a hinge hasp in which the normally fixed plate thereof is arranged for limited sliding movement in a suitable guide that is fixed on the supporting structure for the hasp and wherein 15 the outer staple engaging member of the hasp has slidably and pivotally associated therewith a latching element of a novel construction that is movable through the staple, for locking the hasp thereto.

20 To the attainment of the foregoing, the improvement consists in the invention as hereinafter described and definitely claimed.

In the drawings:

Figure 1 is a plan view of the improvement in applied position.

Figure 2 is a sectional view approximately on the line 2—2 of Figure 1.

Figure 3 is a sectional view on the line 3—3 of Figure 1.

30 Referring now to the drawings in detail, the numeral 1 designates the jamb or post for a swinging door and the door is indicated by the numeral 2. My improvement is especially desirable for employment in

35 connection with garages, but, of course, is not to be restricted to this particular use. In carrying out my invention I secure upon the inner face of the structure 1 a cross sectionally U-shaped guide member 3. This mem-

40 ber is of substantially rectangular formation and is preferably formed from a single strip of metal which has its edges rounded to provide inner and outer parallel members or plates. These members or plates have each

45 alining openings which are preferably arranged adjacent to the corners thereof, the openings 4 in the outer member being preferably larger than the openings in the inner member, and the openings in the inner mem-

50 ber are reamed to receive the flared heads of screws 5 which, of course, are first inserted through the openings 4. The screws enter the structure 1.

There is passed between the members constituting the guide the inner and normally fixed plate 6 of the hasp. This plate is cen-

trally formed with a longitudinal slot or opening 7, and passing through the guide 3 and through the opening 7 there is a bolt member 8 which also passes through the structure 1, the said bolt being engaged by a nut in the usual manner. By this arrangement it will be seen that the plate 6 is held from tilting but is longitudinally adjustable in the guide 3, such adjustment being limited by 60 the contact of the bolt 8 with the end walls provided by the slot 7. This is an important feature of the improvement as the same not only provides for the adjustment of the hasp on the structure 1 but permits of the 65 hasp being set in a suitable distance from the outer edge of the jamb or structure 1.

The plate 6 has its outer edge formed with a central extension, the said extension being rounded outwardly to provide a barrel 9. 75 The outer or swingable element of the hasp is indicated by the numeral 10, the same having its inner end centrally cut-away or bifurcated and the reduced portions thereof rounded inwardly to provide barrels 11 that 80 receive the barrel 9 therebetween, a pivot pintle 12 passing through the alining barrels. By rounding the ends of the elements 6 and 10 of the hasp in opposite directions it will be noted that the swingable or outer section 10 85 thereof is disposed a suitable distance away from the inner section 6, the distance being sufficient to permit of the hasp resting against the plate of a staple when this type of staples are attached to the door 2.

In the showing of the drawings I have illustrated an ordinary U-shaped staple 13 whose pointed legs are forced through the door 2 and the upper ends of the said legs are bent against the face of the door. The 95 swingable section 10 of the hasp is, of course, provided with the usual opening 14 to receive the staple 13 therethrough.

The swingable section 10 of the hasp is formed with a somewhat elongated longitudinally extending centrally arranged opening 15 disposed a distance inward from the transverse opening 14. Through this opening there is passed a double headed rivet 16, or in lieu of the rivet a headed bolt engaged by 100 a nut may be employed. The element 16 is 105 slideable in the opening 15 and passes through the inner end of a spring latch 17. The latch is formed with a strip of spring metal which is centrally bent upon itself and the inner 110 element of the latch is for a distance from the rounded end thereof, rounded or bulged, as

at 18, toward the outer arm or element 19 of the latch. The walls of the inner element of the latch, at the ends of the rounded or bulged portion, exert a frictional engagement against 5 the hasp section 10 so that the latch is held from free movement on the said hasp section 10. The latch may, however, be freely moved through the hasp 13 or out of engagement with such hasp as when the door is to be locked 10 or opened. The spring latch 17 may also be swung on its pivot laterally with respect to the hasp section 10, when the latch is not desired for use.

The simplicity of my construction and the 15 advantages thereof will, it is thought, be understood and appreciated without further detailed description.

While I have illustrated a satisfactory embodiment of my improved device my features 20 of invention are capable of extended application and I do not wish to be limited to the precise structure herein shown and described.

Having described the invention, I claim:

1. A hasp comprising two hinged sections, 25 one of which being mounted on a support and movable longitudinally for a determined distance on said support and the second section having an opening therethrough for the reception of a staple, and said last mentioned

section having a pivotally supported longitudinally movable spring catch thereon to engage with the staple. 30

2. The combination with a structure and a swingable door for closing and opening in such structure, of a cross sectionally U-shaped 35 guide fixed on said structure, a bolt member passing centrally through the guide, a hasp comprising two hinged sections, one of which being received in the guide and having a longitudinal slot therethrough, a bolt member 40 passing through the guide, the slot and the structure for limiting the longitudinal movement of the hasp section through the guide, the second section of the hasp having an opening therethrough, a staple carried by the 45 door, said second section having a longitudinal opening therethrough, a spring latch formed from a plate which is centrally bent upon itself and which has its inner element rounded outwardly so that the portions of the inner element to the opposite sides of the rounded portion will frictionally contact with the hasp section, and a double headed pivot 50 passing through the catch and through the longitudinal slot in the said hasp section. 55

In testimony whereof I affix my signature.

GEORGE J. LESSARD.
